(57) **CLAIM**

The ornamental design for a visual display aid for use in physical training instruction, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a visual display aid for use in physical training instruction embodying my new design;

FIG. 2 is a side view thereof as viewed from the right of FIG. 1, the side view as viewed from the left of FIG. 1 being a mirror- image thereof;

FIG. 3 is a rear view thereof; and,

FIG. 4 is an end view as viewed from one end of FIG. 1, the end view as viewed from the other end of FIG. 1 being a mirror- image thereof.
